UNITED STATES PATENT OFFICE.

JOHN H. PALMER, OF WEST NEW BRIGHTON, NEW YORK.

PAINT.

SPECIFICATION forming part of Reissued Letters Patent No. 11,255, dated July 26, 1892.

Original No. 350,765, dated October 12, 1886. Application for reissue filed October 18, 1887. Serial No. 252,763.

To all whom it may concern:

Be it known that I, JOHN HENRY PALMER, of West New Brighton, in the county of Richmond and State of New York, have invented

5 a new and Improved Paint, of which the following is a full, clear, and exact description.

Prior to my invention the matter remaining after the usual process employed for purifying the oil extracted from flaxseed—that is, lin-10 seed-oil—by subjecting such oil to forced fil-
tration in a filter-press has been of little or no value, as this matter or residuum was consid-
ered as so much waste material; but I have
15 discovered that by combining this residuum
with a certain amount of linseed-oil an ex-
cellent and durable paint (or, more exactly, a
paint-body) may be produced.

My composition consists of the following in-
gredients, which may be combined in the pro-20 portions stated: Residuum of linseed-oil, three
parts, by bulk; linseed-oil, one part. These
ingredients are to be thoroughly mixed ac-
cording to any method commonly used for
mixing paints, such as by grinding in a paint-25 mill. These proportions are suitable for what
is known as "paste-paint." This paint may
be applied as any ordinary form of paint is
applied, being thinned with turpentine to the
proper consistency for working with a brush.

30 Without a pigment it may be used as a primer.
For the further information of the public I
will state that I have found it preferable to
melt the said residuum of linseed-oil by a gen-
tle heat and then to strain it in order to re-35 move foreign particles; also, for ordinary
house-painting I have found the following
proportions the most satisfactory, namely:

residuum of linseed-oil, one part, by bulk; pigment ground in oil, one part, by bulk; lin-
seed-oil or turpentine, about four to six parts, 40
by bulk, or enough to thin the paint to the
proper consistency for working.

I expressly disclaim the use as a paint in-
gredient of the residuum resulting from the
old process of purifying linseed-oil (usually 45
boiled oil) by precipitation, as I am well aware
that this residuum, which is known as "lin-
seed-oil froths," has long been known and used
as an ingredient for paints. The residuum
which I use is the waxy cake which comes out 50
of the filter-presses through which linseed-oil,
and more especially boiled oil, or the said
"froths," has been forced in order to purify or
clarify it.

Having thus described my invention, what 55
I claim as new, and desire to secure by Letters
Patent, is—

1. The herein-described composition of mat-
ter constituting a paint, consisting of the re-
siduum of linseed-oil resulting from the puri- 60
fication of such oil by forced filtration, com-
bined with linseed-oil, substantially as speci-
fied.

2. The herein-described composition of mat-
ter constituting a paint, consisting of the re- 65
siduum of linseed-oil resulting from the puri-
fication of such oil by forced filtration, com-
bined with linseed-oil, in proportions substan-
tially as specified.

JOHN H. PALMER.

Witnesses:

JNO. E. GAVIN,
CHAS. M. HIGGINS.
